UNITED STATES PATENT OFFICE.

ADELBERT FORSYTH, OF MILWAUKEE, WISCONSIN, ASSIGNOR TO MILWAUKEE-RELIANCE BOILER WORKS, OF MILWAUKEE, WISCONSIN.

WATER-HEATER.

1,140,896.

Specification of Letters Patent.

Patented May 25, 1915.

Application filed May 17, 1913. Serial No. 768,263.

To all whom it may concern:

Be it known that I, ADELBERT FORSYTH, a citizen of the United States, and resident of Milwaukee, in the county of Milwaukee and State of Wisconsin, have invented certain new and useful Improvements in Water-Heaters; and I do hereby declare that the following is a full, clear, and exact description thereof.

10 The object of my invention is to provide a simple, economical and effective water-heater, the same being capable of adjustment, whereby the heating capacity is varied to meet the requirements of supply, the said 15 heater being particularly designed for use in supplying hot water to office or flat buildings, although it is understood that it is of general utility.

The arrangement and construction of the 20 heater is such that water at normal temperature is admitted to the lower compartment of a tank, from which compartment it rises through a series of tubes to an upper compartment co-incident to its being heated.

25 Steam is admitted to the upper portion of an intermediate or flue compartment of the tank, at which point it comes in direct contact with the discharge ends of the tubes and the water of condensation from the steam supply is permitted to fill the flue compartment to a predetermined elevation. Thus it 30 is apparent that the cold water entering the tubes from the bottom compartment is first heated by the water of condensation at this

35 point, which water is at a temperature slightly higher than that of the water to be heated, whereby sudden contact between high and low temperatures is avoided. The water to be heated is thereafter gradually

40 increased in temperature as it rises up through the tubes by heat from the water of condensation, which temperature increases gradually to its highest level. Above the level of the water of condensation the supply 45 water is heated by the steam as said water gradually rises through the tubes. Hence in its upward travel to the discharge chamber the said supply of water is gradually heated to a degree corresponding to the

50 temperature of the steam at the upper end of the tube compartment, it being understood that although it is preferable to utilize exhaust steam for supplying the heat, it is within the scope of my invention to utilize live steam if desired. The heated water is

thereafter discharged in the usual manner to supply pipes that are connected to the tank.

The water of condensation is maintained upon a predetermined fixed level by an adjustable float mechanism, which mechanism controls a discharge valve at the bottom of the flue compartment, whereby the water of condensation is exhausted only after all of the available heat therein has been utilized. 60 It follows that to increase the capacity of the heater the elevation of the water of condensation is lowered whereby a greater volume of steam may be utilized for supplying heat to the greater volume of water as it 65 travels through the tank. Furthermore by the arrangement described it is apparent that extreme variations in temperature between the water-supply and heating elements are avoided and hence the connection between the supply tubes and heads of the 70 chambers are rendered less liable to leakage through expansion and contraction.

With the above objects in view the invention consists in what is hereinafter described 80 with reference to the accompanying drawings and subsequently claimed.

In the drawings Figure 1 represents a sectional elevation of a water heater embodying the features of my invention; Fig. 2, a detailed cross-section of a float mechanism for controlling the level of water of condensation, which water is utilized as one of the heating elements, and Fig. 3, an elevation of another form of my invention with parts 85 broken away and parts in section to illustrate structural features.

Referring by characters to the drawings, 1 represents a vertical tank, the ends of which are closed by upper and lower heads 2, 3, respectively, the lower head being provided with feet 3' for the support of the tank. At a predetermined distance from the upper head 2 and secured to the walls of the tank is a flue sheet 4, there being a corresponding 95 flue-sheet 4' similarly secured to the shell of the tank at a predetermined distance from the lower head 3, by which arrangement an upper delivery chamber 5 is formed and a lower receiving chamber 6. The flue-sheets 100 105 are connected by a series of tubes 7, whereby communication is established between the upper and lower chambers. Thus it will be seen that the tank proper is divided into upper and lower compartments and an in- 110

termediate flue compartment 8 for the reception of water of condensation. The lower compartment 6 is adapted to receive a supply of water through a pipe 9 from any suitable source and the upper compartment 5 is provided with a discharge pipe 9', which pipe constitutes the main for a supply system that delivers the heated water to the points of distribution. A steam-supply pipe 10 communicates with the tube chamber adjacent to its upper end, which tube compartment is also provided with a vent-cock 11, whereby air is permitted to escape from said compartment coincident to the delivery of steam thereto in order to prevent air-pocketing. Thus the upper part of the tube compartment constitutes a steam dome and the water of condensation from steam admitted thereto is permitted to fill the compartment to a predetermined level, which level is controlled by an adjustable mechanism.

The mechanism for controlling the level of the water of condensation comprises a condensation pipe 12 which communicates with the tube compartment adjacent to its lower end and an equalizer pipe 13 that communicates with the upper portion of said compartment. These pipes are formed with right-angle extensions which are alined and terminate with unions 14, 14', which unions form couplings for the pipe sections, pipe section 15' being connected to the condensation pipe 12 and being of a length considerably less than the pipe section 15 which is connected to the equalizer pipe. The pipe sections 15 and 15' communicate with a float casing 16, which casing, as shown, is disposed upon the same approximate plane as the level of the water of condensation desired to be maintained within the flue compartment of the tank. The float-casing is provided with a hollow leg 16', into which is journaled a stud 17, one end of which extends out through a stuffing-box and has secured thereto an arm 18. The stud also carries an arm 18' which is disposed within the casing and has secured to its free end a float 19. At a point adjacent to the flue-sheet 4' or bottom of the flue-compartment a waste-pipe 20 is fitted into the shell, whereby the water of condensation may be drawn off at the bottom of the compartment which is normally at a reduced temperature. This waste-pipe carries a controlling valve 20', the stem of which is connected to a lever 21, which lever, in turn, is secured to the arm 18 of the float mechanism by a rod 22. Hence it will be seen that when the water of condensation rises to the level shown, this level will be maintained in the float-casing and, owing to the fact that in this position the float is not at sufficient elevation to actuate valve 20', there will be no discharge of water through the waste pipe. Should the

water-line in the tank rise, however, from this normal selected point, lifting of the float will cause the valve 20' to open and thus permit the water of condensation to drain off, whereby the selected level will be maintained, it being understood that when this level is reached it will permit the waste valve 20' to close.

Should it be desired to increase the volume of water of condensation it is apparent that the float casing and its pipe sections can be disconnected from the couplings 14, 14'. The float-casing is then reversed, the pipe section 15' being secured to the coupling 14, while the long pipe section 15 is connected to the coupling 14'. Thus the position of the entire float-casing is raised, whereby the water level will be maintained at a corresponding line, it being apparent that in this instance the rod 22 which is shown in two parts is lengthened and its sections again secured by the lock-nut.

In the operation of the apparatus water at normal temperature is admitted to the lower receiving chamber 6 and in entering the tubes is in indirect contact with the water of condensation which at this point is also at a low temperature. Thus the supply of water will be slightly heated at this point and gradually increased in temperature as it rises within the tubes to the top level of the water of condensation, at which level said water is at its highest temperature. Thereafter the supply water is increased in temperature as it travels through the tubes which are subjected to the heat of the steam and this heat increases toward the top of the dome or flue-head 4. Hence at the point of discharge into the delivery chamber 5 the temperature of the water has been increased to approximately the temperature of the steam adjacent to the flue-sheet, it being apparent that the supply of water within the upper chamber is also heated by the steam. If the supply of hot water is not sufficient it is manifest that the said supply can readily be increased by lowering the level of the water of condensation so as to increase the area of the steam dome.

Referring to Fig. 3 of the drawings I have shown a heater embodying the features of my invention arranged to be operated horizontally, which horizontal arrangement, in some instances, is desirable. In this modified form of my invention the tank 1 at its intake end is provided with a receiving chamber or compartment 6', from which compartment the water passes through the delivery flues 7' to an intermediate compartment 23 at the opposite end of the tank, and from this compartment the said water is passed through a series of return flues 7'' to the delivery chamber 5'. The delivery chambers 5' and 6' are arranged at one end of the tank and separated by a division

plate 24. Steam is admitted to the flue compartment through pipe 10' and the supply of water is delivered to the receiving compartment 6' by means of a pipe 9'', the said water being discharged from the tank through a pipe 9''', that communicates with the compartment 5'. The arrangement of the float mechanism in this instance is such that the pipe-sections 15 and 15' are in telescopic union with the condenser and equalizer pipes 12 and 13. Hence the float-casing can be adjusted up or down to regulate the height of the water of condensation and after such adjustment the said float-casing is held in its position by a collar 25, which is secured by a suitable set-nut, it being understood that the telescopic connections between the pipes are formed through suitable glands 26, 26'.

20 I claim:

In a water heater having a steam pipe in communication with its top portion and a water pipe in communication with its lower portion of the heater, and a balancing steam pipe in communication with the upper portion of the heater, and a balancing water pipe in communication with the lower portion of said heater the dis-

charge mouths of said pipes being alined and spaced a predetermined distance apart; 30 the combination of a reversible float casing having pipe sections of different lengths extending respectively from its ends, the combined length of said pipe sections and float being approximately equal to the space between the steam and water pipe with which they are adapted to be connected, coupling means for selectively locking the ends of the float pipe sections to the ends of the steam and water pipes whereby the valve-casing is 40 raised or lowered to predeterminedly regulate the water level within the heater, an oscillatory float mounted in the valve casing, an arm carried by the float, a two part rod connecting the arm and valve of the 45 water feed pipe, and means for locking the two part rod in adjusted positions as to length.

In testimony that I claim the foregoing I have hereunto set my hand at Milwaukee in 50 the county of Milwaukee and State of Wisconsin in the presence of two witnesses.

ADELBERT FORSYTH.
